UNITED STATES PATENT OFFICE.

HARRY L. SHAVER, OF SALEM, OHIO, ASSIGNOR OF TWO-THIRDS TO CHESTER G. SMITH AND FRANK H. ARGERSINGER, OF BUFFALO, NEW YORK.

DESIGN FOR A VENDING-MACHINE CASING.

SPECIFICATION forming part of Design No. 34,591, dated May 28, 1901.

Application filed April 24, 1901. Serial No. 57,348. Term of patent 14 years.

To all whom it may concern:

Be it known that I, HARRY L. SHAVER, a citizen of the United States, residing at Salem, in the county of Columbiana and State of 5 Ohio, have invented and produced a new and original Design for a Vending-Machine Casing, of which the following is a specification, reference being had to the accompanying drawing, forming a part thereof.

10 The accompanying drawing is a perspective view of a vending-machine casing embodying my design.

15 The leading or material feature of my design consists of the shape or configuration of the main or body part of the casing, which has the form of a human bust. This bust is dressed in the fashion characteristic of a clown and is mounted on a pedestal.

20 Referring to the drawing, A represents the bust-shaped body of the vending-machine casing, the lower part *a* of which has the form of a rectangular table.

B represents the pedestal upon which the casing is mounted.

The neck of the bust is dressed in a slashed 25 collar C, and the head is surmounted by a cap *d* of sugar-loaf form.

The pedestal shown in the drawing consists of a circular base *e* and an upwardly-tapering flat-sided standard *f*, rising from the base. 30

A slot *g* is arranged in the nose. A row of projections *h* is arranged on the front side of the throat, and the panels of the column are bounded by a rope-like border *i*.

What I claim is—

35 The design for a vending-machine casing, substantially as herein shown and described.

Witness my hand this 22d day of April, 1901.

HARRY L. SHAVER.
